UNITED STATES PATENT OFFICE.

HARRY PARKER, SR., EDWARD SCANLIN, HARRY PARKER, JR., AND HENRY H. SKEVINGTON, OF PHILADELPHIA, PENNSYLVANIA.

CAR-COUPING.

SPECIFICATION forming part of Letters Patent No. 546,864, dated September 24, 1895.

Application filed March 8, 1895. Serial No. 541,022. (No model.)

To all whom it may concern:

Be it known that we, HARRY PARKER, Sr., EDWARD SCANLIN, HARRY PARKER, Jr., and HENRY H. SKEVINGTON, citizens of the United States, residing at Philadelphia, in the county of Philadelphia and State of Pennsylvania, have invented new and useful Improvements in Car-Couplers, of which the following is a specification.

10 The object of our invention is to provide a car-coupler simple in construction and effective in operation by which the coupling of cars is effected entirely automatic and the uncoupling manually by means of levers accessible from either side and the top of the cars to be uncoupled.

A further object is to provide a car-coupler which is not only automatic in coupling, but which may be connected to any known coupler now in use on freight and other cars. The improved coupler is also adapted to connect with couplers of the different types when the latter are disposed higher or lower with respect to the position of the improved 25 coupler without the use of extra links or bent links.

The advantages of the improved coupler may be enumerated as follows: first, quick, sure, and entirely automatic coupling of cars; 30 second, easy and ready uncoupling from either side or the top of the car; third, no losing of links or pins or search for them; fourth, connection can be made with any other coupler now in use on freight-cars and 35 whether they are high or low cars as regards coupling.

Our invention consists of a car-coupler comprising a coupling-bar having a wedge-shaped and sidewardly-bent coupling-hook mounted 40 in a slideway or housing, a link pivoted to a yielding block also contained in said housing, and means for turning the said link.

Our invention further consists of the improvements hereinafter set forth, and pointed 45 out in the claims.

In the accompanying drawings, Figure 1 is a perspective view of two of our improved car-couplers, showing the way in which the coupling of cars is effected. Fig. 2 is a longitudinal vertical section of the improved car-coupler, showing in connection therewith a

draw-bar of the common link-coupler; and Fig. 3 is a longitudinal horizontal section of the improved car-coupler, showing the yielding link connected to a Janney coupler.

55

Referring now to the drawings for a further description of our invention, A is a box-car provided with bumper-heads or buffers *a*, of usual or any preferable construction. B is a housing or slideway for the draw-bar *b* and is fastened to the framework of the car by means of bolts passing through holes in the lugs *b'*. The draw-bar *b* is mounted in the way *b*² of the housing B and is provided at one end with a spear-shaped hook C, extending below the axial line of the draw-bar *b*, forming a shoulder *b*³, Fig. 2. The draw or strain to which the draw-bar is subjected is transferred to the housing B by means of a spring *c*, surrounding the other end of the draw-bar *b* and pressing against a washer of a nut *c'* on the bar *b* and a washer of the housing B.

Directly below the channel or way *b*² and parallel therewith is provided a bore *b*⁴, in which a sliding block *d*, constantly pressed forward by a spring *d'*, is mounted. This spring *d'* is held within the bore by a plug *d*², secured in any manner to the housing, but preference is given to a bolt *d*³, passing through the housing B and plug *d*², as shown in Fig. 3. To the sliding block *d* is pivotally secured a link D in such a manner that it can be turned with its free end above the axial line of the draw-bar *b*, and also that it can yield backwardly or 85 away from the spear-shaped hook C.

The hook C, as before stated, is located below the axial line of the draw-bar *b*, so that the eye *c*² thereof is almost or, if desired, entirely in line with the pivot of the link D. The extreme outer portion of the spear-shaped hook C is bent sidewardly, as indicated in Figs. 1 and 3, so that when two cars are coupled these extreme outer portions lay side by side, allowing also sufficient play when the 95 coupled cars are drawn over curved roads.

To disengage a link D from a hook C or to uncouple cars any means may be provided; but excellent results have been obtained by providing the following mechanism, which is 100 operated from either side or top of a car. This mechanism consists of a lever *e*, pivoted

to one side of the housing B and engaging with its free end one member of the link D, so that when the lever e is turned upward or downward the link D will be moved in the same direction until, as in the downward movement, it is stopped by the projections i on each side of the housing B. The movement of the lever e and link D is effected by a rock-shaft h, journaled in bearings h', attached to the car, and this rock-shaft h is provided with an arm h² and handles h³, the latter extending beyond the sides of the car, so as to be easily operated by hand. The handles h³ are also provided with weights h⁴, so that when the link D is in one or the other position—i. e., for coupling or no coupling—it will be held in either one by the said weights h⁴. The lever e and arm h² are connected by a link h⁵, and the arm h² is further connected with a shifting-rod h⁶, extending to any desired distance to the top of a freight-car or to a platform of a passenger or other car in such a manner that the rock-shaft h, and thereby the link D, can be operated from the top or the platform of a car f in addition to being operated from either side of such car.

The operation of the improved car-coupler may be briefly stated as follows: To couple cars having our improved coupler it is desirable to hold the link D of one coupler out of range of the hook C or link D of the other coupler, as shown in Fig. 1, and this is accomplished by turning the rock-shaft h either by one of the handles h³ or the shifting-rod h⁶. The cars to be coupled are then merely forced together. The link D of one coupler, which is maintained in a horizontal position, rides over the spear-shaped hook of the other coupler and engages the eye c² thereof when or before the bumpers a come in contact. Should, however, the links D of both couplers be in a horizontal position and the cars be forced together, each one will, when one bears upon another, yield backwardly and upwardly until one link leaves the other to ride over the apex of the hook C and drop into the eye c² thereof, as will be readily understood. To uncouple cars it is necessary only to lift the free end of the link D of one coupler engaging the hook C of the other coupler by means of the lever e, link h⁵, and rock-shaft, which is operated either from the sides of a car by the handles h³ or from the top of the car by the rod h⁶.

To couple one car having our improved coupler with a car provided with a common link-coupler, as shown in Fig. 2, the link D may be used, as shown, in which case the attendant in charge must put in the coupling-pin x; but if it is more desirable the common link l, used in the common link-coupler, may be employed, and in such case the link is held in the link-coupler L by means of the pin x, while the link D of our improved coupler is held out of the way by the lever e and rock-shaft h. If now the cars are forced together, the link l rides over the upper edge

of the hook C of our improved coupler and engages the eye c² thereof.

To couple a car having a "Janney coupler" 70 to a car provided with our improved coupler pin x is inserted after the link D is brought into or between the jaws of the hook j, as shown in Fig. 3. However, a common link l, as shown in Fig. 2, may be employed to connect the pin x with the hook C.

Having thus described the nature and objects of our invention, what we claim as new, and desire to secure by Letters Patent, is—

1. A car-coupler comprising a housing a 80 draw-bar provided with a spear-shaped hook held within the same, a yielding link pivoted to a guide block contained in said housing, and means for operating said link, substantially as and for the purposes set forth. 85

2. A car-coupler comprising a draw-bar having a spear-shaped hook as described, a link pivoted to a block yieldingly held in a guide way, a lever in contact with the under side of the link, to form a stop for and keep the link 90 in substantially a horizontal position, and means connected to said lever to elevate the free end of the said link, substantially as and for the purposes set forth.

3. A car-coupler comprising a draw-bar provided with a spear-shaped hook and slidably contained in a way of a housing attached to a car, a link pivoted to a block mounted in a bore or way of the same housing, a spring tending to push the said block and link outwardly and means to turn the said link about its pivot with the said block, substantially as and for the purposes set forth. 95

4. A car-coupler comprising a draw-bar contained within a housing attached to a car, a 100 spear-shaped hook on said draw-bar forming a shoulder abutting the said housing at one end, a spring inserted between the housing and a nut on the other end of the said draw-bar, a link, yieldingly secured to the said 105 housing and means for operating the said link, substantially as and for the purposes set forth.

5. A car-coupler comprising a housing a 110 draw-bar slidably mounted therein, a spear-shaped and sidewardly bent hook on said 115 draw-bar, a yielding link pivoted to a block contained in said housing and means for turning the said link about its pivot consisting of a lever pivotally attached to the housing, a rock-shaft connected to said lever and journaled to the frame of the car and means for operating the said rock-shaft from either side or the top of the car, substantially as and for the purposes set forth. 120

6. A car-coupler comprising a housing, a 125 draw-bar slidably mounted therein, a spear-shaped hook on said draw-bar, a link pivoted to a block yieldingly contained in said housing, projections on said housing to limit the downward movement of the said link, and means for turning the link upwardly about its pivotal connections with the said block, substantially as and for the purposes set forth. 130

7. A car-coupler comprising a housing, a

draw-bar slidingly mounted therein, a spear-shaped and sidewardly bent hook on said draw-bar, a coupling link pivoted to a yielding block contained in said housing, projections on opposite sides of the housing to support the coupling link in substantially a horizontal position, and means for operating the said coupling link, comprising a lever pivoted to the said housing and engaging with its free end one member of the said coupling link, a rock-shaft journaled in bearings attached to a car, an arm on said rock-shaft, a link between said arm and said lever, and handles assisted by weights to maintain the said coupling link in a position to automatically couple cars, or to permanently keep the

said coupling link in a position in which it cannot come in contact with either a pin, hook or link of an adjacent coupler with which the coupler is to connect, substantially as and for the purposes set forth. 20
